ROAST RACK

John Clark Brown, Upper Montclair, N.J.

Application December 4, 1957, Serial No. 700,707

11 Claims. (Cl. 99—426)

This invention relates to roast racks in the form of a self-contained auxiliary grid structure for supporting a roast on the roasting pan in an oven, whereby the roast is held clear of the droppings in the pan while allowing air to circulate freely around the roast.

Such devices usually include a base structure and a pair of roast-receiving cooperative grid members or frames mounted adjustably on the base so that roasts of different shapes and sizes may be accommodated.

The roast rack of this invention provides a construction of exceptional simplicity with a minimum of parts, easy to adjust and effectively to manipulate when transferring the roast from the oven to a serving platter, highly compact when collapsed for packaging or storage, alternatively usable in a special manner as a shallow grid or trivet, highly attractive in appearance both when set up for use and when folded or collapsed for storage, and is adjustable for being used with roasts both very large and very small.

The invention, in one embodiment exemplary thereof, provides a construction having the above criteria, in which a pair of U-shaped frame members are pivotally interconnected in scissors-like fashion so as to be swingable about a common intermediate axis. When set up for use the frame members present a pair of co-operative roast-receiving grill portions above the axis, and two pairs of foot portions provided by the free end portions of the U-shapes. To form the U-shape, these frame members are bent flatwise from a strip of flat stock, with transverse grid bars fixed to the roast-facing edge portions of the flat stock.

In one form, the one U-shaped frame member is disposed between the side portions of the companion frame member so that the frames can be swung into a common plane with the open ends of the U-shapes directed toward each other, for packaging and storage. A rack-positioning member in the form of a bail is hinged to one of the grid portions and may engage a selected pair of notches, a plurality of which is provided on the associated foot end portions of the companion frame. By engaging a selected pair of notches, the included angle between the grid portions may be varied widely for accommodating equally well the smallest roast such as a chicken, up to the largest roast such as a turkey.

Features of this invention lie in a special manner in which the positioning bail member is compactly disposed and secured between the frame members when they are collapsed into the aforementioned common plane for storage.

Other features lie in a special manner of hingedly mounting a pair of handles upon the transverse top end portions of the respective frames. The handles are preferably shaped from wire and are positionable so that the user may lift the rack with the roast from the pan in a convenient and firmly controlled manner, thereupon allowing the roast to slide endwise from the rack onto a serving platter. Alternatively, according to the invention, these handles may serve as auxiliary legs defining an

2

extra shallow position of the grid portions to serve variously as a grill or hot plate, as a cake cooler, or as a trivet. Other features and advantages will hereinafter appear.

5 In the drawings:

Figure 1 is a plan view of the roast rack in collapsed condition for packaging and storage or for use as a horizontal grid.

Fig. 2 is a side view of the roast rack, taken on line 10 2—2 of Fig. 1, illustrating the compactness and showing more clearly the folded-away storage position of the parts.

Fig. 3 is an end view of the roast rack set up for use with the hinged bail positioned to provide a minimum included angle between the grid portions.

Fig. 4 is an end view showing the grid portions with a maximum included angle.

Fig. 5 is a detail sectional view taken on line 5—5 of Fig. 3 of the pivotal connection of the bail with the frame.

Fig. 6 is an end view with the grid portions adjusted to an intermediate included angle.

Fig. 7 is an end view with the grid portions adjusted to another intermediate included angle.

Fig. 8 is an end view with the grid portions adjusted to a maximum included angle.

In the accompanying drawings, a roast rack embodying the features of this invention comprises as main elements a pair of companion frames 10 and 11 formed by U-shaped members or structures having their respective 30 sides or shanks interconnected in scissors-like fashion by means of a pair of pivots 12 and 13 defining a common axis A about which the frames are swingable relative to one another. Although both frame members may be of identical width, pivotally connected with one another, the 35 present example shows the frame member 10 fitted between the sides or shanks of frame member 11 with the width W₁ of member 11 being correspondingly smaller than the width W₂ of member 10.

The U-shape of both frame members 10 and 11 is formed each of a length of flat stock of the width D and of the thickness T, each bent flatwise so as to present a narrow outer edge portion O and an inner or roast-facing edge portion I.

Referring to Fig. 1, the U-shape of the frame member 40 10 has an intermediate transverse body portion 23 parallel to the axis A and a pair of side portions or shanks 24 and 25. Similarly, the companion frame member 11 has a transverse intermediate body portion 26 and a pair of side portions or shanks 27 and 28. According to Figure 5, the frame 10 comprises a grill portion 21 above the axis A and a pair of free end portions or foot end portions 19 and 20. Similarly, the frame 11 comprises a grill portion 14 above the axis A and a pair of foot end portions 19 and 20 below the axis A.

Referring to Figures 3 to 7 showing the device set up for use in cooking a roast or the like, the frame 11 has pivotally connected to the grill portion 14 thereof a positioning member in the form of a bail member 14^a engageable selectively in respective notches or recesses 15,

60 16, 17, 18 provided identically upon each of the foot end portions 19 and 20 of the companion frame 10, whereby the included angle or angular relationship between roast-receiving upper end portions 14 and 21 of the frames is adjustable. Adjustable also in this manner is the vertical distance or elevation E of axis A from the supporting surface S which may be that of a roasting pan.

When not in use and when collapsed for storage or for packaging, the bail member 14^a is disengaged from the notches and swung or folded away to a non-interfering position between the frame members 10 and 11 as the latter are swung into a common plane (see Fig. 1) with the open ends of the frame members directed toward

each other, and with a pair of handles H_1 and H_2 provided on the transverse portions 23 and 26 of the respective frame members. The handles are swung away inwardly (see Fig. 2) to a non-projecting non-interfering storage position, all as will be more fully described below.

The roast-receiving portions of the frame comprise each a series of grill rods 22 parallel to the axis A. The grill rods are of half-round profile with the flat face thereof joining the roast-facing edge portion I of the frames 10 and 11.

The shape of the bail member 14^a comprises an intermediate transverse body portion 31 parallel to the axis A and a pair of side portions 32 and 33 each having an inwardly-bent terminal portion 34 and 35, respectively, whereby the bail member is pivotally connected by way of holes 34^a and 35^a to the sides of the frame member 11 in the manner clearly illustrated in the plan view of Fig. 1 and in the detail sectional view of Fig. 5. It will be seen that the bail member 14^a is swingable about an axis X parallel to the axis A and spaced therefrom a distance K (see Fig. 6). While operatively adjustable in the various roast-receiving positions illustrated in Figures 3 to 7 by engaging respective pairs of notches 15 to 18, the bail member 14^a being of a radial length L, can nevertheless be swung away to an inoperative position on frame member 11 with the transverse body portion 31 of the bail member then lodging in a pair of recesses 36 and 37 provided in sides of frame member 11, and such inoperative position of the bail member being indicated at V in dot-and-dash manner in Figure 6.

With the bail member thus swung away, when the device is then collapsed to the condition shown in Figures 1 and 2, the notched foot end portions of frame member 10 will come to lodge in the spaces 38 and 39 respectively (see Fig. 1) between the side portions of the bail member and the associated respective shanks of the frame member 11. It will be noted (see Fig. 6) that the topmost pair 15 of indentations and the axis X of the bail member have the identical distance K (see Fig. 6) from the axis A so that the inward terminal portions 34 and 35 of the bail member will come to lodge in the notches 15 (see Fig. 1).

The identical handles H_1 and H_2 are specially shaped and disposed in a manner embodying certain features of this invention. These handles being bail-shaped each from a length of wire, are swingably connected to the respective transverse portions of the frame members 10 and 11 in such a manner that normally with the device set up for use, they will hang as shown in Figures 3 to 7. Inwardly the angular movement of the handles is limited by the topmost grill rod 22 acting as an abutment, while the outward swing is limited by the handle abutting against the inner flat face of the flat stock of the frame. The angular movement of the handle is thus limited (see Fig. 7) as between an inner abutment as presented by the point or edge B, and an outer point or edge B_2 , both limit positions being indicated by the positions P_1 and P_2 of the handle shown in dot-and-dash.

Each of the handles H_1 and H_2 is a formed wire shape comprising a transverse middle portion 42 and a pair of side portions 43 and 44 which side portions in turn are formed with terminal eye portions 45 and 46 respectively merging tangentially with the side portions and hung on the transverse portion of the frame through respective holes 47 and 48 therein in such a manner that the handle itself remains interposed at all times between abutments B_1 and B_2 insuring its position to be at all times such as to prevent its being swung around to a position interfering with a roast R placed upon the rack. In this embodiment, desired inner and outer limit positions of the handle are attainable, by having the side portions of the handle bent to form a crook C adapted to engage abutment B_2 while placing the outer end portion 49 of the handle in a substantially horizontal position convenient for manipulation by the user. The crook or angular

formation C on the other hand, allows the handle to engage abutment B_1 in a manner whereby the end portion 49 of the handle may lodge entirely within the storage space assigned to it within the U-shape of the frame (see also Figs. 1 and 2).

The position P_1 of the handles is the one which they assume within the space defined by the frames when the device is collapsed in the manner provided for by this invention and clearly illustrated in Figures 1 and 2; whereas the position P_2 of the handles is the one in which they extend substantially horizontally to be conveniently and firmly grasped by both of the user's hands to lift the device together with the roast from the roasting pan. With the handles in that outward limit position the user may retain a firmly controlled grasp upon the device while transferring the roast onto a serving platter, allowing the roast to slide down along the grill rods 22 from the roast rack onto the platter.

According to the features of this invention, let it be assumed that the device is taken from the shelf or package in the folded or collapsed condition illustrated in Figures 1 and 2; in that condition the overall dimensions of the device are substantially those of a flat slab substantially square in plan view with the sides M and N (see Fig. 1) and the height G (see Fig. 2).

In this condition the positioning member or bail member 14^a is folded away and confined between the frame members in the manner above described by lodging in the one pair of recesses 36 and 37 in frame member 11, as well as in the other pair of recesses 15 in frame member 10. The bail member is secured in this stored position by the recessed extreme ends or tips T_1 and T_2 of frame member 10 comprising the transverse portion of the bail member in those recesses 36 and 37. The handles H_1 and H_2 are folded inwardly to assume the storage position clearly shown in Fig. 2.

Although in this fully-collapsed position the device may serve as a level grill or hot plate if desired, it can now be set up for use as a roast rack in various adjusted positions with predetermined variations of the angular relation between the roast-receiving members to suit various sizes of the roast to be cooked. Beginning, for instance, with the position shown in Fig. 4, the bail member engages the lowest pair of notches 18 providing the largest included angle attainable by the use of the positioning member, at the same time reducing the vertical elevations E of axis A to a corresponding minimum. From this position the user may pull up on the handles while pressing them together slightly to cause the bail member to disengage itself from the lowest pair of notches and, overriding subsequent pairs of notches upwardly, he may cause the bail member to come to rest engaging in the topmost pair of notches 15 corresponding to the position of the parts shown in Fig. 3 where the included angle is a minimum and the elevation of axis A a maximum above the surface of the roasting pan. Adjustments intermediate these extreme positions of Figures 3 and 4 are shown in Figures 6 and 7 attainable either from the Figure 4 position by manipulating the handles substantially in the manner above indicated, or from the Figure 3 position by the user's one hand grasping the right-hand handle, while thumb and forefinger of the other hand grasp the left-hand handle allowing the remaining other fingers of the left hand to grasp and disengage the transverse portion of the bail member to guide or ease it into a selected lower intermediate pair of notches.

According to this invention, the device is further capable of the adjustment illustrated in Fig. 8, whereby there is attainable an extremely shallow or obtuse included angle that lies beyond the range provided for by the row of notches 15, 16, 17, 18, so that a very large roast or a large steak or the like, can be accommodated. According to that feature, the bail member is disengaged from the notches and is allowed to lodge upon the recessed tips T_1 and T_2 of the free end portions of frame member

10, while the handles H_1 and H_2 are positioned to serve as supporting members or auxiliary legs braced under an acute angle U against the horizontal supporting surface. When so conditioned, the device may serve also alternatively as a trivet having what amounts substantially to only point contacts A_1 , A_2 , A_3 , A_4 , with the supporting surface or platter or table whereby heat transfer from the trivet or through the trivet to the supporting surface can be minimized.

Other modes of applying the principles of the invention may be employed, change being made as regards the details described, provided that the features stated in any of the following claims or the equivalent thereof, are employed.

I claim:

1. A roast rack comprising a pair of companion frame members pivotally interconnected intermediate their ends to be swingable relative to each other about a common axis to an operative roast-receiving position providing a pair of grill portions above said axis and corresponding foot portions below said axis, and means engageable to maintain said operative position and disengageable to allow said frame members to be swung into a common plane, which frame members are U-shaped structures each formed from a length of flat stock bent flatwise with the closed ends of the U-shapes constituting the grill portions and the free end portions constituting the foot end portions, said engageable means comprising a bail member having a transverse intermediate portion and a pair of side portions formed with inwardly bent terminal portions in pivotal engagement with the associated sides of one of the grid portions to be swingable about an axis parallel to said common axis and engageable in a selected pair of a series of pairs of recesses formed along the foot end portions of the companion frame, each side of said grill portion having a recess for receiving the transverse portion of the bail when the same is swung outwardly to an inoperative position substantially in a plane with said grill portion, the foot end portions of the companion frame being shaped to clear the transverse portion as well as the inwardly bent terminal portion of the bail member when the frames are swung into said common plane.

2. The roast rack according to claim 1, in which at least one of said foot end portions is shaped and adapted to confine the transverse portion of the bail member in its respective recess.

3. The roast rack according to claim 1, in which the U-shape of the one frame member is dimensioned to fit between the shank portions of the U-shape of the companion frame member, and the foot end portions of the wider frame member are disposed to lodge in the respective spaces between the shank portions of the narrower frame member and the respective side portions of the bail member when the frames are swung into a common plane.

4. A roast rack comprising a pair of companion frame members pivotally interconnected intermediate their ends to be swingable relative to each other about a common axis to an operative roast-receiving position providing a pair of grill portions above said axis and corresponding foot portions below said axis, means engageable to maintain said operative positions and disengageable to allow said frame members to be swung into a common plane, said frame members being in the form of U-shaped structures, each formed from a length of flat stock being bent flatwise with the closed end of the U-shape constituting the grill portions and the free ends of the U-shape constituting the foot portions, each grill portion having a series of grill rods parallel to said common axis fixed to the roast-facing edge portion of the flat stock, and a pair of handles in the form of bail members swingably mounted upon the transverse portions of respective U-shapes with inner and outer abutments provided by said grill portions for limiting the angular movement of the handles to stay

5

clear of the roast, said inner abutment being disposed to allow said handles to be positioned and accommodated inoperatively within the space defined by the respective U-shapes and the grill rods, said outer abutment being disposed to allow said handles to be positioned in generally laterally outwardly projected position relative to said frame members.

5. The roast rack according to claim 4, in which the inward abutment is provided by the grid rod nearest the handle.

6. The roast rack according to claim 4, in which the inward abutment is provided by the grid rod nearest to the handle, and the outward abutment is provided by the inner flat face of the flat stock.

15 7. The roast rack according to claim 4, in which the handles are shaped each from a length of wire having a transverse intermediate portion and a pair of side portions each terminating in an eye engaging in a respective hole provided in the flat stock of the frame members.

8. The roast rack according to claim 4, in which the handles are shaped and disposed in such a manner as to serve in their outward limit position as a pair of outwardly diverging auxiliary supporting members when braced against a supporting surface to provide a shallow included angle between the grid portions while said engageable means are disengaged.

9. The roast rack according to claim 4, in which the handles are shaped each from a length of wire having a transverse intermediate portion and a pair of side portions each terminating in an eye merging tangentially with the side portion, the eye-forming portion of the wire passing through a respective hole in the flat stock of the frame member, each handle having the eye-forming portions disposed to surround the roast-facing edge portion of the frame member, the inner abutment comprising the grid bar nearest the handle, the outer abutment being provided by the inner flat face of the flat stock being engaged by the side portions of the handle.

10. The roast rack according to claim 9, in which each handle is formed with a bend in the side portions thereof with the apex of the bend pointing inwardly.

11. A roast rack comprising a pair of companion frame members pivotally interconnected intermediate their ends to be swingable relative to each other about a common axis to an operative roast-receiving position providing a pair of grill portions above said axis and corresponding foot portions below said axis, means engageable to maintain said operative position and disengageable to allow said frame members to be swung into a common plane, and a pair of handles mounted upon the top ends of respective frame members and positionable for serving as a pair of auxiliary supporting members providing a shallow included angle between the grid portions with said engageable means remaining disengaged said handles being positionable between inner and outer abutments provided on the frame members, said outer abutments defining the operative position of the handles to extend horizontally away from the frame members and also defining the position of the handles when serving as auxiliary supporting members.
